UNITED STATES PATENT OFFICE.

RICHARD COLLINS, OF SPRINGFIELD, MASSACHUSETTS, ASSIGNOR TO HIMSELF AND WILLIAM C. McCLALLAN, OF SAME PLACE.

LOOM.

SPECIFICATION forming part of Letters Patent No. 239,936, dated April 12, 1881.

Application filed April 26, 1880. (No model.)

To all whom it may concern:

Be it known that I, RICHARD COLLINS, of Springfield, Massachusetts, have invented certain Improvements in Looms, for which no foreign patent has been applied for or obtained with my knowledge or consent, and of which the following is a specification.

My invention relates more particularly to improvements in the harness and shuttle motions and the rocker to the picker-stick.

In the drawings, Figure I is a plan view, with all of the upper parts of a loom removed to show the harness and shuttle motions. Fig. II is a partial front elevation of a loom, showing the harness and shuttle motions, together with the construction of the rocker to the picker-staff and its seat. Fig. III is a side elevation of so much of a loom as shows the connection between the driving-shaft and cam-bearing shaft for directly governing the harness and shuttle motions; and Fig. IV is a modification of the combined harness and shuttle operating cams shown in Fig. I, to adapt them to the operation of three sets of harness.

Upon the shaft B, which is geared directly to the driving-shaft C, is fixed the cylinder D, provided with the cam-groove d, within which groove works the end of the crank-arm e of rock-shaft E. The shaft E works in bearings f framed to the loom, and has the end of its crank-arm e provided with the roller g, while its other end carries the pulley h, to which are attached the ends of straps k m, for raising and lowering the harness. The roller g does away with friction in the contact of the end of the crank-arm e with the walls of groove d of the cylinder D.

It will be seen that the rotation of the cylinder D, by partially rotating pulley h, raises and lowers the harness a distance proportionate to the periphery of hub h, to which the ends of straps k m are attached, so that in practice it is only necessary to proportion the size of pulley h to the arc of rotation given crank-arm e to insure the proper angle being given to the shed of the warp. The groove d is formed in cylinder D, so as to oscillate the hub h to raise and lower each of two sets of harness during one revolution of shaft B, and

is peculiar in being so formed as to have two dwells at opposite sides of the cylinder, which serve the purpose of holding the harness stationary at the moment the shuttle is thrown. In Fig. II the crank-arm e is shown as just 55 entering the rest or dwell, the intermediate walls of the groove giving a uniform vibration to the arm e.

Fixed upon shaft B are cylinders H H', provided with the cam-grooves o o', in which work the ends of vibrating levers I I'. The levers I I' are hinged upon studs or projections v v' from the frame J of the loom, so as to receive horizontal vibrations from the revolution of cylinders H H'. The ends of levers I I', 60 playing in grooves o o', are provided with rollers to diminish friction, while their other and longer ends are attached by rigid connections w w' to the picker-sticks K K'. The cam-grooves o o' in cylinders H H' are reverse 65 counterparts of each other, and each is formed so as to cause its picker-stick to make one throw during the revolution of shaft B, while the cams o o' are so relatively arranged upon the shaft B as to cause the picker-sticks to alternate 70 to make two throws of the shuttle during one revolution of shaft B, and thus cause the motion of the shuttle to bear the proper relation to the movement of the harness. The walls of the grooves o o', by coming at all times 75 in contact with the ends of levers I I', so govern the motions of the picker-sticks as to cause them to deliver their blows and return to their positions for receiving the blow of the shuttle without superfluous vibration, to the avoidance 80 of the aberration that frequently causes the rocker to leave its seat and the shuttle to be thrown over the boxes.

In Figs. I and II of the drawings an operating-cylinder for two sets of harnesses is 85 shown, in combination with cams for a shuttle-motion to correspond; but without a departure from the principle of this invention a cylinder may be substituted, as shown in Fig. IV, to contain more than one cam-groove to 90 operate three or more sets of harnesses. The changed arrangement of rocker and strap-pulley to correspond with the duplication of cam-grooves in the harness-cylinder is such as will suggest itself to any mechanic, the shaft E in 95 100

Fig. IV being shown as having a duplicate placed beside it. It may have another sleeved upon it, with a longer crank-arm. The harness and shuttle motions thus described are 5 noiseless, compact, and positive-acting at all times.

In Fig. II is shown the construction of a rocker and seat for picker-stick, which insures a uniform and easy rock to the stick, as well as 10 prevents the rocker from being entirely thrown off its seat, operating as follows: Upon the lower side of plate *y* is the spur *i*, having a bearing-surface as near as possible coincident to a curve described from the center of oscillation of the rocker; and from the rear of this 15 rocker, projecting downward and inward through a guiding-slot, 10, left open in the outer end of plate *y*, is a horn, *j*, whose end bears on the surface of the spur *i* as the rear of the 20 rocker rises and falls, or comes sufficiently near the bearing-surface of spur *i* to prevent the rocker from being abnormally moved, and thereby compelling the picker-stick *K* to be in 25 its proper place in the shuttle-box. The horn *j* at the base of spur *i* comes against the bottom of plate *y*, to always retain the rocker upon its seat.

As the portion of the mechanism of a let-off motion for the yarn-roll of a loom shown in 30 Fig. I forms part of an application for a patent now before the Office for an improvement in looms, filed by me June 9, 1880, and embracing said device in its claim, I hereby disclaim any part of such device as forming part 35 of this patent.

Having described my invention, what I claim is—

1. The combination of revolving shaft *B*, cylinder *D*, having one or more grooves, *d*, shaped to produce a dwell in the motion of the harness while the shuttle is propelled through the opened warps by the action of cams *H H'*, harnesses with their straps or other means of connecting them with pulley *h*, rock-shaft *E*, working in bearings at right angles to shaft *B* and provided with crank-arm *e*, and pulley *h*, with cam-cylinders *H H'*, arranged upon shaft *B* to be revolved therewith, and provided with cam-grooves *o o'*, vibrating levers *I I'*, pivoted at points intermediate to their ends, rigid connections *w w'*, and picker-sticks *K K'*, whereby, through the rotation of shaft *B* common to cams *D* and *H H'*, the harnesses are alternately opened and closed and the shuttle is positively propelled through the 55 opened warp at the moment of its dwell, substantially as shown and described.

2. The rocker provided with the horn *j* and guiding-projection, in combination with the seat *y*, adapted to be attached to the frame of 60 a loom, and provided with slot 10 to receive the guiding-projection of the rocker, and spur *i*, as and for the purpose shown and described.

RICHARD COLLINS.
